(57) **CLAIM**

The ornamental design for a crimp tool, as shown and described.

DESCRIPTION

FIG. 1 is a perspective view as seen from the front and top side of a crimp tool in a closed position showing the new design;

FIG. 2 is a perspective view as seen from the front and top side of a crimp tool in an open position showing the new design;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top view thereof; and,

FIG. 8 is a bottom view thereof.

The portions of the crimp tool illustrated in broken lines form no part of the claimed design.
